BOX WITH HINGED CLOSURE
 Daniel M. Pearl, Skokie, Ill., assignor to
 Sealatron Corporation, Chicago, Ill.
 Filed Aug. 27, 1964, Ser. No. 392,482
 3 Claims. (Cl. 190—41)

This invention relates generally to improvements in portable containers such as shoeboxes and hatboxes. More particularly, the invention is directed to hinge means, closure means, and carrying means for such containers. Also included within the scope of this invention are methods of fabricating the containers.

Various hinge arrangements and closure and carrying means have heretofore been provided for containers such as shoeboxes and hatboxes. These known prior art constructions have been relatively complicated in form and costly and time consuming in construction. They have had one or more objectionable features which have limited and impaired their usefulness. Accordingly the prior art devices have not found universal application and have not been adopted without reservations.

More specifically, it is the aim of the present invention to provide a novel hinge arrangement for a hatbox or a similar container which arrangement is of simple form and which is nevertheless completely effective for the intended purpose when applied to structures having pivotal lids attached thereto. A related aim of the invention is to provide a simple closure mechanism for a hatbox or the like, which closure mechanism also includes an integral carrying strap by means of which the box may be transported.

A principal object of the invention is to provide a novel hinge structure for a hatbox, shoebox, or the like having an improved integral hinge by means of which the cover is fastened to the box body.

Another object of the invention is to provide a closure and carrying means for containers such as shoeboxes and hatboxes which closure means is of simple form and is effective to prevent accidental opening of the box or container when being carried.

Still another object is to provide a novel carrying handle and strap which is of sturdy construction and is disposed so that the weight of the container and the goods stored therein aids in holding the container closed when being carried.

Other objects of the invention include the following: to provide a novel box hinge, carrying and closing arrangement, and over-all construction which can be economically produced; to provide a box which is sturdy in construction and neat in appearance yet which incorporates a minimum of material and fittings to ensure economy in production; and to provide methods by which the box or container of the invention may be fabricated.

Other and further objects and advantages of the invention will become apparent from a reading of the following specification taken in conjunction with the drawing in which:

FIGURE 1 is a perspective view of a closed shoebox, hatbox or the like incorporating the teachings of the present invention;

FIGURE 2 is a perspective view of the box, similar to FIGURE 1, but showing the box in an open position;

FIGURE 3 is a vertical cross sectional view of the box taken along the line 3—3 of FIGURE 1;

FIGURE 4 is a horizontal cross-sectional view of the rear wall and hinge section of the box taken along the line 4—4 of FIGURE 3;

FIGURE 5 is a vertical cross sectional view taken along the line 5—5 of FIGURE 2; and

FIGURE 6 is an enlarged fragmentary cross sectional

view depicting a detail of constructing as indicated more generally in FIGURE 5.

Referring more particularly to the drawing, there is shown in FIGURES 1 and 2, for the purpose of illustrative disclosure, a preferred embodiment of the box of the invention, incorporating the teaching thereof. The box 10 illustrated includes a body 11 and a cover 12, the cover 12 being permanently attached to the body 11 by means of a hinge element 13. In the box illustrated, which is generally heart-shaped or triangular in form, the body 11 includes a base wall 16 and an endless side wall 17 integrally joined at its lower peripheral edge 18 to the periphery 19 of the base wall 16, to provide an open top container. The box cover 12 is contoured to correspond to the contour of the body 11 of the box and comprises a top wall 21 integrally joined at its periphery to a depending endless side wall 22. The over-all dimensions of the top wall 21 of the cover 12 are slightly greater than the dimensions of the base wall 16 of the box body so that the cover fits over the box body in a contiguous nesting relation, as illustrated in FIGURES 1 and 3.

The hinge 13 by means of which the cover 12 is joined to the body 11 of the box consists of a tab or flap 25 which forms an integral part of a substantially flat rearwardly disposed portion 26 of the side wall 17 of the box body 11. As illustrated in FIGURE 2 and as shown more clearly in FIGURE 3, the hinge tab 25 is formed by providing two laterally spaced through slits or slots 29 and 30 in the rear wall portion 26 of the body of the box. The slits 29 and 30 extend downwardly from the top edge 31 of the wall 26 for a distance substantially equal to the vertical height of the side wall or depending flange 22 of the cover 12. In use, the line of flexure of the hinge is defined by a line connecting the lower extremities of the slits 29 and 30. In a preferred embodiment of the invention the lower extremities of the slits terminate in openings 33 and 34 which are generally rounded or curved to minimize any tendency of the structural material from which the box is fabricated to rip or tear. Fastening means are provided for attachment of the hinge tab 25 to the corresponding rear side wall 36 of the cover 12. In the preferred embodiment of the box depicted, rivets 40 and 41 are used as fastening means to provide firm attachment of the tab 25 to the wall 36 on the inside thereof.

As illustrated in FIGURES 1, 2 and 5, the box is provided with a combination box closure and handle assembly which comprises a flexible strap 45 which slides under a bridge 47 to fasten the cover and the box body together and to provide a carrying means which may be held when transporting the box. In the particular embodiment depicted, the strap 45 is illustrated as a loop which is fastened on the inner side of the depending side wall or flange 22 of the crown 49 of the cover by means of a rivet 50. The point of attachment of the carrying strap to the cover 55 is preferably diametrically opposite the position of the hinge assembly. The bridge 47 beneath which the flexible carrying strap and closure member 45 passes consists of a bar or band 52 extending parallel to the base 16 of the box and supported outwardly from the side wall 17 of the box on spacers to provide a slot or opening to permit passing the strap between the bar 52 and the wall 17. The bar 52 is attached to the wall 17 of the box by means of spikes, rivets 56 and 57, or other suitable mechanical means. In a preferred embodiment of the box 60 closure and handle assembly a reinforcing or strengthening plate 58 is provided on the inner wall portion of the box adjacent the point of attachment of the bar 52 to ensure that the bar and rivets will not be pulled from the side wall of the box body.

The preferred method of fabricating or constructing the box or carrying case of the invention is described be-

low. In the particular example of the box illustrated, the structure includes five (5) principal assemblies: an encapsulated top board or top wall and a gusset board or side wall, which form the cover of the assembly, an encapsulated bottom or base wall and an encapsulated bottom gusset board, which form the body of the assembly and a handle assembly. The top board or top wall 21 of the cover, as shown in FIGURE 3, consists of four components including an outer sheath 60, a foam pad 61, a chipboard stiffener 62 and a liner sheet 63. The four elements are superimposed and aligned and the foam pad and the chipboard stiffener are then sealed between the two outer sheets to provide a one-piece composite assembly. Sealing of the two outer sheets is preferably by a heat sealing technique, these sheets, in preferred embodiments of the invention, being fabricated for a plastic or related material. The top gusset board or side wall 22 of the cover 12 consists of three components, an outer cover sheet 65, a chipboard stiffener 66, and a liner sheet 67. These three layers are superimposed and the outer sheet is sealed to the liner sheet along one edge. The ends of this assembly are then joined by heat sealing using a butt type of seal. In a preferred procedure, a reinforcement 68 is provided to strengthen and to cover the butt seal portion. The encapsulated bottom board or base wall 16 of the box body is similar in construction to the top board and includes an outer sheet 70, a foam pad 71, a chipboard stiffener 72 and a liner sheet 73. As previously described with reference to the top board, the composite is assembled and the outer and liner sheets are heat sealed along the periphery. The bottom gusset board or side walls 17 of the box body 11 is assembled in a manner similar to that described with reference to the top gusset board or wall 22 of the cover. However, prior to assembly, the chipboard element 75 is die-cut and scored to provide two end portions each defining a section which is movable. Upon assembly, these end portions are joined to provide a flat and movable surface which constitutes the mechanical hinge of the invention. The chipboard 75 is encapsulated between an outer cover sheet 76 and an inner liner sheet 77 and heat sealing is provided around the outer edge as well as in the area of the slotted portions bounding and adjacent the hinge. The end of the entire assembly is then joined and butt sealed. On the outer surface of the joined assembly adjacent the hinged portion a reinforcement 78 is provided to cover the butt seal and to add additional strength to the hinge. As indicated schematically in FIGURE 5, the handle assembly 45 consists of an outer cover 80, an encapsulated filler board 81 and a second outer cover 82. The outer covers being heat sealed along the edges to encapsulate the filler board.

In assembling the final components to provide the composite unitary structure, the top board assembly is placed on the top gusset assembly and side sealed around the periphery to join the two providing an integral top cover assembly 12. The handle or strap 45 is then riveted to the front or crown 49 of the cover 12. The bottom board assembly and bottom gusset board assembly are then sealed together to provide an integral unit which constitutes the body 11 of the box. The bridge 47 is then attached to the front of the box body 11 at the crown 49. Finally, the cover and the box body are riveted together at the rear to attach the cover to the hinged element which is integral with the wall of the box body.

While for purposes of illustrative disclosure, the fabrication and construction of the subject invention has been described with reference to particular materials, it is apparent that many equivalent materials may be used. For example, although vinyl polymers and vinyl copolymers are preferred cover and liner sheet materials, board has been referred to as the stiffening or bodying agent and is a preferred material because of economic considerations. However, rigid or semi-rigid plastics may be substituted for the chipboard. Suitable materials in-

clude polystyrenes, polyesters, and other thermo-plastics as well as thermo-setting polymeric materials. The internal padding may be fibers, natural or synthetic rubber, or urethane or any equivalent material.

While disclosures of preferred embodiments of the box and of preferred methods for assembly and fabrication of the box of the invention have been provided, it will be apparent that numerous modifications and variations thereof may be made without departing from underlying principles of the invention. It is, therefore, desired by the following claims to include within the scope of the invention all such variations and modifications by which substantially the results of this invention may be obtained through the use of substantially the same or equivalent means.

What is claimed is:

1. A plastic container of flexible plastic sheet material, said container comprising a body having a base wall, an endless side wall integrally joined to said base wall at a peripheral edge thereof and extending upwardly therefrom, a cover for said container, said cover having a top wall contoured to correspond with the contour of said base wall, and an endless side wall integrally joined to said top wall at a peripheral edge thereof and depending downwardly therefrom, said body of said container and said cover for said body of said container comprising walls of multilayer construction including a liner sheet, a cover sheet, and a stiffener sheet therebetween and coextensive therewith to define composite unitary structures, said side wall of said cover being adapted to fit over and to surround the outer surface of upper portions of said side wall of said body in contiguous nesting relation therewith; a hinge integral with and formed in and of said side wall of said body, said hinge comprising a tab integral with and pivotally connected to said side wall of said body along a flexure line substantially parallel to a plane defined by the top edge of said side wall of said body and intermediate upper and lower peripheral edges of said side wall of said body, said side wall of said body having a pair of laterally spaced through slots extending downwardly from said top edge of said side wall of said body to said flexure line defined by juncture of said tab with said side wall of said body, said slots defining lateral limits of said tab, joinder means connecting said tab to a corresponding portion of said side wall of said cover, and a combination container closure and handle assembly comprising a flexible strap having a free end and a fixed end, means permanently connecting said fixed end of said strap to said side wall of said cover at a position diametrically opposite the point of attachment of said cover to said body, bridge means affixed to and supported on said side wall of said body at a position corresponding to a point of connection of said strap to said cover, said bridge means defining with said side wall of said body a through slot adapted to receive said free end of said strap therethrough; whereby upon closure of said cover over said body said strap may be pulled through said slot to provide a closure for said container and whereby said strap also serves as a handle for said container.
2. The handle assembly set forth in claim 1 wherein said flexible strap comprises a loop attached to the underside of said side wall of said cover.
3. The container of claim 1 wherein said cover comprises a padded top board consisting essentially of a liner sheet, a cover sheet, and a stiffener sheet and a re-

silent pad therebetween, all coextensive to define a composite unitary structure.
